so that flare 15 engages shoulder 4, again spreading or expanding the sleeve and allowing the lead to enter and slide into place without resistance.

In the form of the pencil shown in Figs. 13 to 18, the lead feeding structure is reversed; the outer barrel 18 having a longitudinal groove 19 to engage the pin 20 on the lead advancing plunger 21 in the inner barrel 22; the latter having a helical groove 23 cut therethrough.

The lead gripping sleeve 24 in this case does not project into the lead-fitting bore 25 of the tip 26, but terminates in a flare 27 at its outer end which cooperates with the flaring shoulder 28 on the inner end of the bore 25. The functioning of this sleeve however, when a lead is being inserted or advanced, is obviously the same as in the first described type.

I claim:

1. A mechanical pencil comprising a lead-receiving barrel, a tip on the barrel from the outer end of which the lead projects for writing, means in the barrel to advance the lead through the tip, a lead gripping member in the tip, said member comprising a longitudinally split spring sleeve tending to contract and normally gripping the lead, an outwardly facing flared element on the sleeve, and a cooperating flared shoulder in the tip to engage said element and cause the element to spread upon advancing longitudinal movement of the sleeve.

2. A pencil as in claim 1, with an additional flare element on the inner end of the sleeve facing away from the outer end thereof, and a cooperating flared shoulder on the adjacent end of the barrel, the distance between the flare elements on the sleeve being less than that between the shoulders.

3. A mechanical pencil comprising a lead-receiving barrel, a tip on the barrel from the outer end of which the lead projects for writing, means in the barrel to advance the lead through the tip, a longitudinally split spring sleeve mounted for limited longitudinal movement in said tip and normally contracted in lead-gripping position, and cooperating means on the sleeve and the tip to cause said sleeve to expand and release the lead when the sleeve has reached a predetermined position within the tip.

4. A mechanical pencil comprising a lead-receiving barrel, a tip on the barrel from the outer end of which the lead projects for writing, means in the barrel to advance the lead through the tip, a longitudinally split spring sleeve mounted for limited longitudinal movement in said tip and normally contracted in lead-gripping position, an inclined face on the interior of said tip, a flared element on said split sleeve, said element adapted to engage and ride upon said inclined face when said sleeve is moved a predetermined distance toward the outer end of said tip to expand said sleeve to lead-releasing position.

WILBUR D. MEASE.
